WINDOW SASH

James Gerow Wilkin, New Hurley, N. Y.

Application June 14, 1944, Serial No. 540,352

4 Claims. (Cl. 20—56.3)

1

It is a matter of common knowledge that when it is desired to clean a window pane, considerable difficulty is experienced in wiping close to the mullions. The foregoing difficulty having been appreciated, the present invention aims to provide mullion structures which are removable reading from the sash, the sash enclosing a single pane which, after the removal of the mullions, may be cleaned readily.

It happens, moreover, that occasionally it is desired to change the mullion pattern of a window, and the present invention aims to supply a novel means whereby a mullion of one pattern may be substituted for a mullion of another pattern.

A further object of the invention is to supply a flexible mullion which, on account of its flexibility, may be mounted readily on a window sash and with equal facility be removed therefrom.

Within the scope of what is claimed, the structure described and shown may be changed, without departing from the spirit of the invention.

In the accompanying drawing:

Fig. 1 shows, in front elevation, a window sash equipped with the device forming the subject matter of this application;

Fig. 2 is a vertical transverse section on the line 2—2 of Fig. 1, parts being broken away;

Fig. 3 is an enlarged section taken through one of the seats;

Fig. 4 is a section on the line 4—4 of Fig. 3;

Fig. 5 is an elevation showing a portion of the mullion structure, including one construction by which the mullion structure is made flexible;

Fig. 6 is a sectional view showing the mullion structure partially folded, to permit the assembly thereof with the frame;

Fig. 7 is a sectional view looking toward one of the seats which receive the mullion-ends;

Fig. 8 is a section on the line 8—8 of Fig. 7;

Fig. 9 is an elevation similar to Fig. 5, but disclosing a modified structure wherein flexibility in the mullion structure is obtained by means other than that disclosed in Fig. 5.

Fig. 10 is a sectional view taken through a portion of the sash and a portion of the pane.

In carrying out the invention there is provided, in the building material art, a sash S, comprising a frame 1. In its inner edge, the frame 1 is supplied with a continuous recess 2, wherein the marginal portion of a pane 3, of glass or the like, is held by putty 2a, or equivalent means.

At spaced distances, the inner portion of the frame 1 is provided with outwardly tapering seats 4. Preferably a single pane 3 is employed, the

2

pane occupying the entire area bounded by the frame 1.

In each seat 4 is disposed a grip G, made of metal or other suitable material. The grip G comprises a U-shaped shank 5, the constituent parts of which are in contact. The shank 5 bears at its outer end against the frame 1, as shown in Fig. 3, at the base of the seat 4. The side portions of the shank 5 are spaced as shown at 6, the side portions being resilient and terminating in laterally extended, resilient loops 7.

Mullion structures are disposed on opposite sides of the pane 3 and extend across the pane. The mullion structures may be made in various ways, without departing from the spirit of the invention. Preferably, but not of necessity, each mullion structure includes a horizontal rail 8, including a long part 9 and a short part 10, disposed in alinement. The inner ends of the parts 9 and 10 of the horizontal rail 8 abut along a line indicated by the reference character 11 in Fig. 5.

Each mullion structure includes a vertical rail 12, comprising parts 14 disposed on opposite sides of the horizontal rail 8. The abutment line 11 between the parts 9 and 10 of the rail 8 coincides with one longitudinal edge of the vertical rail 12. A resilient strip 15, made of metal or other suitable material, connects the parts 14 of the vertical rail 12, and extends across the member 9 of the horizontal rail 8, the strip 15 being secured at 16 to the rail parts 14. A similar strip 17 extends across the strip 15, at right angles thereto, and is secured at 18 to the members 9 and 10 of the horizontal rail 8.

From the foregoing, it will be noted that the rails 8 and 12 are flexible, the flexibility being secured by means of the strips 15 and 17. The strips 15 and 17 are let into the rails, so that the rails present a smooth inner edge to the glass pane 3.

Another vertical rail 19 may be provided, as shown in Fig. 1, this rail comprising parts disposed on opposite sides of the member 9 of the horizontal rail 8, the constituent portions of the vertical rail 19 being connected by a hinge strip like the hinge strip 15 of Fig. 5, the hinge strip 17 being omitted. In general, the constituent parts the horizontal and vertical rails may be made in various ways, it being necessary, merely, that there be a sufficient number of hinges so that the mullion structures are flexible.

The rails of the mullion structures terminate in fingers 20, shaped to be received in the seats 4. The fingers 20 are somewhat narrower than

the mullion rails proper and, therefore, there are formed at the ends of the mullion rails proper, on opposite sides of the fingers, transverse shoulders 21 and 22, the shoulder 22 being disposed adjacent to the pane 3, and the shoulder 21 being disposed at the outer surface of the mullion rail. About the fingers 20 are disposed compressible gaskets 23, and the shoulders 21 and 22 press the gaskets against the inner edge of the frame 1 and make watertight joints. This construction preferably is carried out in connection with the outer mullion structure only.

In the inner surfaces of the fingers 20, recesses 24 are formed. The recesses 24 are shaped to receive the resilient loops 7 of the grips G. The recesses 24 and the loops 7 constitute releasably interengaged elements on the fingers 20 and on the grips G, respectively.

To position the mullions, the grip G at one end of the mullion to be positioned, is placed within the seat 4 and the fingers 20 at one end of the mullion, are positioned within the recess. The fingers are forced against the loops 7 of the grips, the loops 7 moving into the recesses 24 of the fingers. The opposite end of the mullion is now positioned in a similar manner, with the result that the mullion is secured against flexing and consequently, held in place, under normal conditions.

As shown in Fig. 6, each mullion structure may be molded at the hinges 15 and 17, so that the fingers 20 can be withdrawn from the seats 4. This enables both mullion structures to be removed, facilitating a cleaning of the pane 3, there being no obstructing mullions in the path of the cloth or other device used to clean the pane.

It is not necessary that the mullions be provided with hinge strips 15-17. Thus in Fig. 9, the mullions 30 are of one-piece construction, and are made of material which has inherent resiliency.

If the operator desires to change the mullion pattern, the mullion structures shown in Fig. 1 may be removed and be replaced by mullion structures of a different design, the seats 4 providing for such an operation. Referring to Figs. 7 and 8, the seats 4 which are not occupied by the fingers 20 of the mullion rails may be closed by plugs 26, having side recesses 27 for the reception of the loops 7 of the grips G, the plugs terminating in laterally extended heads 28, com-

pressible gaskets 29 being interposed between the heads 28 and the frame 1, to prevent leakage into the seats 4.

The device, in either of its forms, is simple in construction, but will be found thoroughly advantageous to carry out the operations described in the opening portion of this specification, and elsewhere therein.

What is claimed is:

1. A window sash comprising a frame, a pane carried by the frame, said frame having cut-out portions formed in the inner edges thereof, providing seats, a mullion including rails, fingers formed at the ends of the rails and adapted to be fitted within the seats, and members mounted within the seats adapted to grip the fingers positioned within the seats, holding the fingers and mullion against displacement.

2. A window sash comprising a frame, a pane carried by the frame, said frame having cut-out portions formed in the inner edges thereof, providing seats, a mullion including rails, fingers formed at the ends of the rails adapted to be fitted within the seats, said fingers having recesses formed therein, yieldable gripping members positioned within the seats and extending into the recesses of the fingers, securing the fingers and rails against displacement.

3. A window sash comprising a frame, a pane carried by the frame, said frame having cut-out portions formed in the inner edges thereof, the cut-out portions extending along the edge of the pane, mullions positioned on opposite sides of the pane and embodying rails, fingers on the free ends of the rails adapted to fit in the cut-out portions of the frame, said fingers having recesses, and gripping members having curved arms adapted to fit within the recesses of the fingers, frictionally engaging the fingers and normally holding the mullions against displacement.

4. A window sash comprising a frame, a pane carried by the frame, said frame having cut-out portions formed in the inner edges thereof providing seats, a mullion including hingedly connected rail sections, the ends of the rail sections adapted to extend into the cut-out portions of the frame, and means within the cut-out portions adapted to engage the ends of the rails securing the mullions in position against accidental displacement.

JAMES GEROW WILKIN.
